UNITED STATES PATENT OFFICE

2,040,919

CIRCUIT CLOSER

Samuel P. Caldwell, Hamden, Conn., assignor to
The Engineering and Research Corporation,
New Haven, Conn., a corporation of Connecticut

Application April 7, 1932, Serial No. 603,699

1 Claim. (Cl. 200—159)

This invention relates to a functionally and structurally improved form of circuit closer or switch.

It is an object of the invention to provide an apparatus of this character which will embody a minimum of moving parts and in which such parts as are necessary may be manufactured at relatively low cost and assembled to provide a unitary and simple apparatus capable of operating over long periods of time with freedom from mechanical or electrical difficulties.

A further object of the invention is that of furnishing a device of this character in which operation thereof will assure a complete and proper closing of the circuit and in which a structure is presented which will properly exclude moisture or foreign elements from the structure of the circuit closer.

Another object is that of constructing a switch which may be conveniently operated by the hand of the user, although within the province of the present invention it might be otherwise operated.

With these and other objects in mind, reference is had to the attached sheet of drawings in which:

Fig. 1 is a sectional side view;

Fig. 2 is a plan view with certain of the parts broken away to disclose the underlying construction;

Fig. 3 is a sectional side view showing the switch proper;

Fig. 4 is a plan view thereof but again having certain of the parts broken away to disclose the underlying construction;

Fig. 5 shows a form of construction slightly different from that illustrated in Fig. 1.

In these several views the numeral 10 indicates the base of the unit and upon which a top or cap 11 may be mounted and secured as for example, by screws 12. The base 10 may be formed with one or more openings, through which electrical leads 13 may extend, it being obvious that electric conductor conduits may be coupled to the casing at this point.

As shown in Figs. 1 and 2, the cap or top 11 may be formed with an opening defined by a centrally upstanding flange 14 which may terminate in an outstanding bead or lip 15. An actuating element in the form of a rod or pin 16 slidably extends through the cap opening and mounts at its upper end a head 17 having a downwardly extending flange 18 which snugly embraces the flange 14, and more especially the lip 15 thereof, without such contact, however, preventing relative movements of the parts. At

its lower end the actuating element is enlarged as at 19 for engagement with the switch proper.

This switch, in the embodiment illustrated, preferably takes the form of a relatively rigid and concave disc 20, to which one of the conductors 13 is connected, this disc centrally mounting a contact stud if this appears desirable. Overlying the disc 20 is a contact element which may take the form of a resilient or flexible strip 22, the inherent tendency of which is to extend in spaced relation to the disc 20 or contact element 21, but which may be flexed into engagement with one of these elements. The second conductor 13 is secured to the strip 22 and with a view to normally preventing electrical connection between the disc and strip, a body or layer of di-electric material, such as rubber 23, is interposed between these elements. Moreover, as shown in Fig. 4, layers of suitable material, such as rubber, are provided above the strip and below the plate, and thus form a housing 24 which—after suitable vulcanization or other treatment—serves to effectually enclose the switch mechanism and protect the same from the action of moisture, foreign materials, etc.

It is obvious from the foregoing that the operator, by simply pressing against the head 17, may exert sufficient pressure upon the strip 22 to cause the same to be flexed into contact with the element 21 or the plate 20, thus closing the circuit. Due to the construction provided, a unit is furnished in which there is a minimum probability of damage occurring to the parts, either due to abuses in operation or due to the action of the elements. The unit will have an extremely long life and if desired may be locked by, for example, positioning the bail of a padlock (indicated in dotted lines of Fig. 1) to extend between the top of the cap proper and the lower edge of the flange 15.

It will be noted that by the present construction the switch unit is supported, for example, on the ledge or flange 24 of the base and is prevented from shifting by contact with the walls of the complementary recess forming a part of the cap. Also, as shown in Fig. 1, a proper channel is provided through which the leads 13 may be threaded.

In certain instances it may be desired to actuate the switch by other than by application of direct pressure. It is obvious that if this result is desired, the stem 16 may, for example, be provided with a pin 25 which rides against a ledge surface 26 formed in the interior of the cap and providing in effect a cam. Thus, by simply turning the knob 17, the stem is caused to shift down-

wardly to an extent adequate to assure a closing of the circuit. At the end of its travel the pin may ride into a notch formed in the surface 26, as shown in Fig. 5, so that a deliberate manipulation 5 of the parts is necessary to thereupon effect an opening of the circuit. It is also apparent that if operation of the unit in this manner is desired, a handle 27 may be secured to the knob for the purpose of facilitating a turning of the latter.

10 From the foregoing it will be understood that among others, the several objects of the invention as specifically aforenoted, are achieved. Ob-
15 vious numerous changes in construction and re-
arrangements of the parts may be resorted to without departing from the spirit of the invention as defined by the claim.

Having described my invention, what I claim as new and desire to secure by Letters Patent is:

A circuit closer including a disk, a contact element extending from said disk, an inherently resilient strip insulated from said element and extending from a point adjacent the edge of the disk across the same and to a point substantially diametrically opposite said first point, the ends of said strip being maintained substantially against movement with respect to said disk and the body of said strip normally clearing said contact element, and a pair of disks of flexible ma- 10 terial and of a circumference greater than said first named disk, said pair of disks being disposed beyond the outer faces of said strip and said first named disk and the edges of said latter disks being secured to each other at points beyond the 15 edge of said first named disk.

SAMUEL P. CALDWELL.
